UNITED STATES PATENT OFFICE.

WILLIAM F. BUCK, OF CHICAGO, ILLINOIS, AND HENRY W. JACOBS, OF TOPEKA,
KANSAS.

SUPERHEATER.

971,522.

Specification of Letters Patent.

Patented Oct. 4, 1910.

Application filed June 2, 1910. Serial No. 564,673.

To all whom it may concern:

Be it known that we, WILLIAM F. BUCK and HENRY W. JACOBS, citizens of the United States, and residing at Chicago, in the county of Cook and State of Illinois, and Topeka, in the county of Shawnee and State of Kansas, respectively, have invented certain new and useful Improvements in Superheaters, of which the following is a description, reference being had to the accompanying drawings, which form a part of our specification.

The object of our invention is to provide a detachable superheater which is simple in design and construction; the superheater being composed of two compartments adapted for use on a Mallet articulated locomotive.

A further object of our invention is to provide a superheater of the construction herein described wherein all the steam pipe connections will be located on the outside of the boiler shell, and in which the shell of the superheater compartments will form the intermediate part of the boiler shell.

Another object of our invention is to provide a superheater that will be held perfectly rigid and in correct alinement with the boiler, and also permit of ready access being had to all steam pipe connections and allow any leaks to be detected and easily repaired.

In the drawings: Figure 1 is a partial longitudinal vertical sectional view of the intermediate part of the boiler of an articulated Mallet compound locomotive; a portion, to wit:—the cylinders and the connections to and from the cylinders being shown in side elevation. Fig. 2 is a cross section taken on the line A—B of Fig. 1, looking in the direction of the arrows. Fig. 3 is a longitudinal vertical sectional view of the intermediate part of the boiler of an articulated Mallet compound locomotive, showing a modification. Fig. 4 is a cross sectional view taken on the line C—D of Fig. 3, looking in the direction of the arrows. Fig. 5 is a longitudinal sectional view of the boiler of an articulated Mallet compound locomotive, with the cylinders and connections in elevation, showing another modification. Fig. 6 is a partial longitudinal sectional view showing another modified form of our invention, wherein two tube or flue sheets are employed.

Our invention consists of superheating means for the steam before it enters the pres-

sure cylinders and other means for resuperheating the steam after it leaves the high pressure cylinders and before it enters the low pressure cylinders; the superheater comprising two compartments, both compartments being located within the intermediate part of the boiler.

We have illustrated the invention,—which is of the smoke-tube type, wherein the smoke tubes pass continuously through both superheating means or compartments when employing the form shown in Figs. 1, 3 and 5,—as more especially adapted to an articulated Mallet compound locomotive.

In the construction shown in Figs. 1, 3 and 5 the superheating means or compartments are separated by an annular flue sheet 1, thus providing means for superheating the steam for the high pressure cylinders and means for resuperheating the steam after it leaves the high pressure cylinders and before it is delivered to the low pressure cylinders. This flue sheet 1 is suitably riveted or otherwise secured within the outer shell, as clearly illustrated. 3 are the boiler tubes through which the gases of combustion pass and are discharged into the combustion chamber 4, with which the superheater tubes 5 communicate, thus allowing the gases to continue in their passage from chamber 4, through the tubes 5 and into a second combustion chamber 6. Communicating with this chamber 6 are the feed water tubes 7 which convey the gases of combustion forward to the smokebox of the boiler (not illustrated) from which point they escape through the smokestack; the smokebox or forward end of the locomotive is not shown as it is of the usual well known construction. A steam pipe 8 conveys the steam from the throttle in the steam dome to the first compartment or superheating means 9; this compartment being intermediate of the flue sheet 1 and the sheet to which the ends of the tubes are welded adjacent to chamber 4.

The compartment or superheating means 9 is provided with a suitable number of baffle-plates 10, extending from side to side, see Fig. 2. The baffle-plates 10 are so arranged as to compel the steam to flow in a lateral direction from side to side so as to come into contact with the different tubes 5 passing through the compartment. It is apparent from the construction shown in Fig. 2 that the steam entering at the top of

the compartment through pipe 8 is compelled to pass downwardly from one side of the compartment to the other a number of times until it reaches the lower part of the compartment, when it will pass out through the steam pipes 11, 11, and be discharged into the high pressure cylinders A. The location of the steam pipes 11, 11, to opposite sides of the locomotive where they connect with cylinders on each side, is set forth in Fig. 2. After the steam has passed through the high pressure cylinders it is discharged through the steam pipes 12, 12, see Fig. 2, and conveyed to the second compartment or superheating means 13, see Fig. 1. As the superheater tubes 5 also pass through the compartment 13 it is apparent that the steam will be resuperheated. Compartment 13 is provided with a series of vertically arranged baffle-plates 14, see Fig. 4, which are alternately secured to opposite sides on the interior of the shell, thus providing a passage for the steam first at the upper part of the compartment and then at the lower portion thereof, as is clearly shown in Fig. 4. This arrangement of the baffle-plates compels the steam to pass through a circuitous route and in contact with the tubes 5. The steam pipes 12 enter the compartment 13 from the sides, see Fig. 4, which compels the steam to flow upward and downward in contact with the tubes 5 until it reaches the center portion of the compartment when it will be allowed to flow through the steam pipe 15, see Figs. 1 and 4, and be conveyed to the low pressure valves and cylinders. After the steam has spent its energy in the low pressure cylinders it is allowed to escape through the exhaust stand into the smoke-box and pass out through the smoke-stack in the usual manner.

The superheater section is removably secured in place by the rings 16 and 19 which are fastened to the ends of the superheater section and take against or register with similar rings 17 and 18 secured to the shell of the boiler. The rings of the superheater section and those of the shell of the boiler may be clamped or drawn together by suitable bolts 20. In order to support the superheater section while it is being put in place and also to assist in carrying its weight, we prefer to provide the lugs 16' and 17'; the lug 16' is secured to the ring 16 on the superheater section and takes onto the lug 17' which is secured to the ring 17, see Fig. 1. It is of course understood that a similar set of lugs are secured to the opposite side of the shell. The ends of the tubes 5 are preferably welded to the tube sheets or plates at the points 21, 21; while the tubes are rolled into the intermediate flue sheet 1 which separates the two compartments. The combustion chamber 4, located be-

tween the boiler and the high pressure superheater 9 is provided with a manhole 22, and the combustion chamber 6, located between the low pressure superheater 13 and the feed water heater is also provided with a manhole at 23. These holes permit a man to enter either combustion chamber to make any necessary repairs. Both combustion chambers 4 and 6 are also provided with cinder hoppers 24 and 25 so as to permit of the removal of cinders or unconsumed products of combustion that may become lodged in either or both of these chambers. The shell of the superheater, like that of the boiler, may be covered with lagging as at 27, see Fig. 3.

In Figs. 3 and 4 we have illustrated our invention adapted to a modified form of locomotive wherein the courses of the steam and hot gases of combustion are practically identical with that described when referring to the construction illustrated in Fig. 1 wherein the superheater means are shown located in front of the high pressure cylinders. In the construction illustrated in Figs. 3 and 4, the superheater is located above the high pressure cylinders. In this construction the saddle casting, which supports the superheater and braces the engine frame between the high pressure cylinders, is divided in a horizontal plane thereby forming the joint 28; the two sections of the saddle casting being securely fastened together by bolts 29. By forming the saddle casting in the manner just described, it permits of the easy removal of the superheater from the boiler and engine frame, this being accomplished by first disconnecting the steam pipes, (all of which are to the outside of the shell of the superheater); removing the bolts 29 from the joint 28 in the saddle casting and the bolts 20 from the connecting rings 16, 17 and 18, 19.

In Fig. 5 we have shown a further modification, wherein the shell of the superheater is directly connected by rivets or bolts to the shell of the feed water portion of the boiler, forming the lapped seam as at 31. By reason of the fact that the connection or seam is located in the forward combustion chamber 6 where a steam tight joint is not required, the connection between the two shells may be made in the manner shown and described. The other end of the superheater section is removably secured to the boiler-shell by the connecting rings 16 and 17; these rings being preferably made to fit within each other as shown, being secured together by bolts 20 as previously described. The course of the steam and the gases of combustion is similar to that defined when describing the construction shown in Fig. 1.

In Fig. 6 we show another modification of our invention wherein the superheater tubes 5, 5 of the two superheating compartments 130

are made separate, the ends of the tubes 5, 5', being welded to the two tube or flue sheets 21'. In this construction the tube sheets 21' are provided with the rings 18' and 19', which are so formed as to fit into each other, the one ring being provided with a V-shaped projection or face which takes into a corresponding groove in the opposite ring. The rings are clamped or drawn together by the bolts 20', thus forming a tight joint between the two sections of the superheater. The course of the steam and that of the gases of combustion are similar to that described in speaking of the construction 15 shown in Fig. 1.

In the construction shown in Fig. 6, the saddle support 30 is placed back of the high pressure cylinder, thus allowing the superheater to be built directly above the high 20 pressure cylinder, thereby reducing the space occupied by the combustion chamber 4. This construction obviates the necessity for a long combustion chamber wherein the 25 gases would become cooled, and furthermore permits of a more compact construction. With this construction the superheater may be readily removed by disconnecting the external steam pipe connections, and it is not necessary to disconnect the joint in the saddle, as would be necessary with the construction 30 shown in Fig. 3.

It is apparent from the construction shown in Fig. 6, that the entire superheating means for both the high pressure cylinder 35 and for the low pressure cylinder may be readily removed by removing the bolts 20' in the rings 16, 17 and 18, 19, after disconnecting the external steam pipe connections; or when desired, either one of the superheating 40 means may be easily removed, by loosening bolts 20' in the connecting rings 18', 19' and also the bolts whereby the rings at the other end of the section are secured together.

45 It will be noted that all steam pipe joints are made to the outside of the shell of the superheater where they can be easily repaired and any leaks readily detected; whereas if the steam pipe joints were located in the interior of the shell, it would be necessary to put the locomotive in the round house, allow it to cool and then put what is known as a water test on the boiler in order to definitely locate any defective 50 steam joints; after repairing the defective joint the water test would again have to be applied in order to determine whether it was properly done. On the other hand, with our invention where the steam pipe joints 55 are all located on the outside of the shell, (which is made possible because the outer casing or shell of the superheating means comprises a continuation of the boiler-shell), the engine would not have to make this de- 60 lay as the work to be done would all be on

the outside of the shell where it could be done even if the boiler-shell were hot, as the joints could be tested by allowing steam to enter the superheater.

With the shell or casing of the superheater constituting an intermediate section of the boiler shell, no space is lost between the superheating means and shell of the boiler as is true in constructions heretofore employed. For this reason the superheater section may be made shorter without loss of any superheating power; and by reason of the fact that the shell of the superheater constitutes a section of the boiler shell, all steam pipe connections either leading to 70 or from the superheater can be made to the outside of the shell, thus permitting any leaks to be readily detected and adjustments 75 easily made from the outside. This is quite an important feature and obviates the very 80 serious objections heretofore encountered.

We have shown and described our invention as applied to an articulated Mallet compound locomotive, but we do not wish to be understood as limiting ourselves to 90 this particular type of locomotive; nor do we wish to be understood as broadly claiming the invention of superheating means.

We have shown and described what we believe the preferred manner of applying 95 our invention, but it will be readily understood that alterations may be made in the arrangement and in a number of minor details without departing from the spirit of our invention, and we do not wish to be 100 understood as limiting ourselves to the exact constructions shown and described, but

What we claim as our invention and wish to secure by Letters Patent is—

1. A superheater comprising a cylindrical 105 shell or drum having smoke tubes extending in a longitudinal direction therein, said shell being located between two combustion chambers and forming an intermediate section of the boiler shell, means whereby said section 110 is divided into two compartments to form separate superheating means, and means whereby said section is secured in place to be readily removed.

2. A locomotive provided with a section 115 intermediate of the boiler and the feed water heater and constituting a portion of the boiler shell, combustion chambers located at both ends of said section, smoke tubes extending in a longitudinal direction in said 120 section and communicating with combustion chambers at both ends, means whereby said intermediate section is divided into two compartments to form separate superheating means, and means whereby said intermediate 125 section is removably held in place.

3. A superheater of the class described whose outer casing forms an intermediate section of the boiler shell, means located to the outside of said casing whereby the steam 130

is led to and from said superheater, and interlocking rings secured to the ends of the casing and to adjacent portions of the boiler shell whereby the superheater section is removably held in place.

4. A superheater of the class described comprising a cylindrical casing which forms an intermediate section of the boiler shell, retaining rings secured to the ends of said 10 casing and to adjacent portions of the boiler shell whereby the casing is removably held in place, and means located on the intermediate section and the boiler shell whereby said section is supported on the boiler shell.

15 5. In a locomotive, the combination of a boiler, cylinders, and a superheater, the shell of the superheater forming an intermediate section of the boiler shell, means intermediate of said section and the boiler shell whereby said section is secured in place to be readily removed, combustion chambers formed within the boiler shell and located at opposite ends of said intermediate section, with steam connections between the boiler, 20 superheater and the cylinders, located outside of the shell.

25 6. In a locomotive, a superheater of the

class described having a casing which forms an intermediate section of the boiler shell, a combustion chamber located at each end of 30 said section, means whereby the casing is divided into two compartments to form separate superheating means, and rings secured to the ends of said section and the adjacent portions of the boiler shell, adapted to register and form a tight joint.

7. In a locomotive, a superheater of the class described provided with an outer casing which forms an intermediate section of the boiler shell, combustion chambers 40 formed at opposite ends of said section, the superheater being composed of two compartments to form separate superheating means, and means whereby the compartments are readily removable.
